UNITED STATES PATENT OFFICE.

AUGUST J. MUELLER, OF CHICAGO, ILLINOIS.

WALL CONSTRUCTION.

Application filed January 5, 1922. Serial No. 527,155.

To all whom it may concern:

Be it known that I, AUGUST J. MUELLER, a citizen of the United States, residing at Chicago, in the county of Cook and State of Illinois, have invented a new and useful Improvement in a Wall Construction, of which the following is a specification.

My invention relates to tile or block construction, and more particularly to a unit 10 made of cement or clay that is shaped so that when a plurality of units are assembled in tiers they are interlocked with each other and with any suitable metallic reinforcing device. 15 More specifically my unit is adapted for use in the building or erection of chimneys, silos, elevators, bins and similar structures, although it is capable of use in connection with rectangular structures, such as foundations, walls, and even partitions and the like. 20 The primary object of this invention resides in providing blocks or units that interlock with each other and provide spaces between the units and the tiers so that vertical and 25 horizontal reinforcing rods may be utilized therewith and after a portion, or the whole structure, has been erected the spaces may be filled with a moist cement that will, when set, be cast in a manner to provide a complete monolithic structure.

As is well known a moist or comparatively wet mixture of cement and aggregates provides, when dried out and set, a harder and more durable element than a mixture of 35 a more plastic nature. Also the wet mixture may be easily poured, and requires no tamping or agitation in order to completely distribute it to all corners and crevices of the cavity it is desired to fill. In the filling of 40 hollow wall structures, it has heretofore been the practice to use the plastic mixture notwithstanding its requirement of tamping because it has been found the wet mixture will invariably leak out of the joints between the 45 blocks and run down the surfaces of the wall causing a considerable waste and resulting in an unsightly appearance.

I have designed my unit so that the meeting edges of a plurality of units will provide interstices into which may be forced a quantity of cement or mortar to fill the same and seal the structure between the units, after which a wet mixture of cement and aggregates may be poured into the inner hollow space between the opposite faces of the

blocks and will be retained against leakage. Many other objects will be apparent to others after an understanding of my invention is had, and therefore need not be herein explained. I prefer to carry out my invention in substantially the manner hereinafter described, and as illustrated in the accompanying drawings that form a part hereof and which are, in a sense, merely diagrammatic for the purpose of illustration.

In the drawings:

Figure 1 is a horizontal sectional view of a fragment of a chimney or silo wall constructed with my improved blocks.

Figure 2 is a view similar to Fig. 1 showing the manner of using my block for rectangular structures such as foundations and the like.

Figure 3 is a vertical sectional view of one of the blocks, and a fragment of an adjacent block, the view being taken on line 3—3, Fig. 1.

Figure 4 is a perspective view of a block. Referring to the drawings, it will be seen the block preferably comprises oppositely disposed outer and inner plates or members 5 and 6, respectively, that are of corresponding shape and in the rectangular or straight wall construction (Fig. 3) are of the same dimensions, but in the curved wall construction (Fig. 1), the inner plate or member 6 is of slightly less width than, but the same height as the opposite outer member 5. A transverse vertical web or neck 7 connects the two members of the block adjacent opposite vertical edges of the respective members. The block might be described as of a Z-section or distorted I-section, plates or members 5 and 6 forming the parallel arms or cross pieces of the Z or distorted I and web 7 the connecting arm or body of the structures. At the corners of the Z-section or I-section the block has extensions 8 and 9 projecting in opposite directions that form continuations of the respective outer and inner plates or members 5 and 6 so that said plates or members are offset with relation to each other, and these extensions, which are in substance vertical flanges, are rounded on their outer edges and curved inwardly, as at 10 and 11, respectively, so that the end of each extension projects towards the opposite plate or member of the block.

The opposite ends of the plates or members are provided with rather abrupt hook-

shaped extensions that provide shoulders 12 and 13 at the ends of the outer surfaces of the respective members, said extensions continuing inwardly and away in a short curve 5 (of segmental shape in cross-section), as indicated at 14 and 15 in the drawings. I prefer to provide grooves 16 upon the upper edges of members 5 and 6, and correspondingly shaped shoulders 17 in the lower edges 10 of said members so that the tiers or superposed blocks will be interlocked with each other in the wall constructed therewith, and in laying a wall I prefer to overlap or break joints as in the usual manner of tile and 15 brick laying. The curvature of part 10 and the adjacent portion of shoulder 12 and hooked end 14 is such that the blocks must be moved towards each other in an oblique direction when being placed in position instead of moving them straight or horizontally towards each other during the laying 20 operation, and after being set in position a tapered crevice or interstice α will be provided that extends inwardly from the outer 25 surface of the wall between adjacent blocks and at the inner portion of the joint, between the blocks, is another crevice γ so that a quantity of cement or mortar may be inserted in said crevices to seal the joints and 30 form a key.

Upon the top of each tier or layer of blocks, I place a horizontal reinforcing bar 18, and in order to accommodate the bar the upper edge of web 7 is preferably convexed, 35 as at 19, to provide a recess for the bar, as shown in Fig. 3 of the drawings. Vertical reinforcing bars 20 are positioned adjacent web 7 of each block and in the respective tiers these rods will be disposed adjacent one 40 side and the opposite side of alternate superposed blocks. After the wall has been either partially or wholly constructed in the manner hereinbefore described, a quantity of 45 grout or wet cement and aggregates is poured into the spaces bounded by the outer and inner members and the webs of the blocks. The mixture is fluid enough to pour down to the bottom of the wall past each web and entirely fill the spaces, and, 50 crevices α being sealed, acts as a cork and prevents the leakage of this wet mixture through the joints.

There is little or no difference between the 55 blocks for the cylindrical walls for chimneys, silos and the like, and those for straight walls, except that in the latter instance a special corner block is utilized that has its outer plate or member 5 provided with a lateral extension 21 disposed at right angle 60 to the plate to form the corner of the wall; the end of this angular extension having the curved end 8 to interengage with shoulder

12 and segmental portion 14 of the adjacent block, as seen in Fig. 2 of the drawings.

What I claim is:

1. A wall formed of blocks arranged in tiers, each block comprising an inner and an outer member spaced apart and connected by a transverse web, the adjacent ends of contiguous members forming said wall having interfitting extensions whereby recesses are provided interiorly and exteriorly of each inner and outer member, plastic keys inserted in said recesses to seal the same, and a filling of semi-fluid material poured into the space between said inner and outer members and retained therein by the keys to provide a monolithic structure.

2. In a monolithic wall, a plurality of elements forming an integral part thereof, each element provided with inner and outer members spaced by a connecting web, the adjacent vertical edges of contiguous members in the wall having extensions that interfit and provide recesses interiorly and exteriorly of said members, plastic keys inserted in said recesses whereby to seal the same and semi-fluid concrete deposited between said inner and outer members to provide a solid structure therewith.

3. In the construction of a solid wall structures a plurality of shaped elements for providing facing and reinforcement therefor each element comprising inner and outer face members, a connecting web spacing said members, the adjacent vertical edges of contiguous face members having extensions for loosely interfitting with adjacent elements whereby recesses are provided between the same, and plastic keys inserted in said recesses whereby the shell formed by said element is adapted to receive and retain concrete in semi-fluid condition and to provide therewith permanent integral facing and reinforcement for a solid structure.

4. A wall formed of blocks arranged in courses, each block comprising inner and outer members spaced apart and connected, a segmentally shaped extension at one vertical edge of each member, an element at the opposite vertical edge of each member arranged to interfit with the segmental extension of an adjacent block and provide interstices therebetween, plastic keys sealing said interstices, and a filling of semi-fluid concrete poured into the space between the inner and outer members and retained therein by the keys to provide a monolithic structure.

Signed at Chicago, county of Cook, and State of Illinois, this 28th day of December, 1921.

AUGUST J. MUELLER.
